(57) **CLAIM**

The ornamental design for a plant watering apparatus, as shown and described.

DESCRIPTION

FIG. 1 is a top perspective view of a new design for a plant watering apparatus;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front view thereof; and,

FIG. 10 another front view thereof.

The broken line showing of a border between the top and bottom portions of the plant watering apparatus is included for the purpose of illustrating portions of the article and forms no part of the claimed design. The remaining broken lines are included for the purpose of illustrating environmental structure and form no part of the claimed design.

1 Claim, 10 Drawing Sheets
